ABSTRACT OF THE DISCLOSURE

Methyl- β -hydroxydodecyl sulfoxide useful as a detergent and foam stabilizer.

The present invention relates to novel methyl-2-hydroxyalkyl sulfoxides which are useful as detergents and foam stabilizers.

This application is a continuation-in-part of our co-pending application, Ser. No. 365,487, filed May 6, 1964, which in turn was a continuation-in-part of our applications, Ser. Nos. 725,505, filed Apr. 1, 1958, and 60,546, filed Oct. 5, 1960, all now abandoned.

Alkyl sulfoxides having a long chain fatty acid residue are known to have surface active properties. U.S. Patent No. 2,787,595 to Webb discloses the use of alkyl sulfoxides as the essential active ingredient in detergent compositions. According to Webb, the sulfoxides may be employed per se as the essential active ingredient in detergent compositions, but preferably are employed in combination with inorganic "builder" salts. It is also stated in the patent that other synthetic detergents may be employed as detergency supplements in combination with the sulfoxides and that foam stabilizers may be added.

In accordance with the present invention, novel compounds are provided having the following formula:

wherein R is a hydroxyalkyl radical having from 8 to 18 carbon atoms. The methyl-2-hydroxyalkyl sulfoxides are preferred, and a preferred species of this group of compounds is methyl-2-hydroxydodecyl sulfoxide,

These compounds are also known as methyl- β -hydroxyalkyl sulfoxides.

It has been found that the presence of small amounts of the sulfoxides of this invention improves the stability of the foam produced by agitating aqueous solutions of suds-producing materials selected from the group consisting of anionic, amphotolytic and nonionic organic synthetic detergents. The preferred methyl-2-hydroxydodecyl sulfoxide is exceptionally stable in the presence of household bleach.

The term "suds-producing materials selected from the group consisting anionic, amphotolytic and nonionic organic synthetic detergents," as employed herein, is intended to include those anionic, amphotolytic and nonionic compounds which are commonly employed as the essential active ingredient of suds-producing detergent compositions.

Suitable anionic suds-producing organic synthetic detergents include the alkyl aryl sulfonates, such as sodium dodecyl benzene sulfonate or ammonium pentadecyl benzene sulfonate, and the methyl taurates, such as Igepon TK-32, a sodium N-methyl-N- "tall oil acid" taurate, and Igepon TE-42, an N-methyl acyl taurate derived

2

from tallow. Also included are the sulfated fatty alcohols, such as sodium lauryl sulfate and ammonium lauryl alcohol sulfate; the sulfated polyethylene oxide esters of resins or fatty acids, such as the ammonium salt of sulfated nonyl phenol condensed with four moles of ethylene oxide; and Sipon LT-6, a triethanolamine lauryl alcohol sulfate.

Suitable nonionic suds-producing organic synthetic detergents which may be employed according to this invention include Oronite NI-8589, a dodecyl phenol condensed with more than 10, i.e., 20 to 30 moles of ethylene oxide; Triton X-100, an alkyl aryl polyether alcohol, i.e., octylphenol condensed with 10 moles of ethylene oxide; Tergitol NP-14, an alkyl phenol polyethylene glycol ether; Neutronyx 600, an aromatic polyglycol ether condensate; Sterox AJ, a tridecyl alcohol condensed with 10 moles of ethylene oxide; and Sterox CD, a tall oil condensed with 10 moles of ethylene oxide.

Also suitable are Deriphate No. 154, a tallow disodium betaine dipropionate, and sodium cocoglycinate. These are amphotolytic substances.

Conventional soaps and inorganic "builder" salts, such as the phosphates, silicates, sulfates and the like, are not included within the term "suds-producing materials selected from the group consisting of anionic, amphotolytic and nonionic organic synthetic detergents" used herein, although these materials can be used as auxiliary agents in the compositions of this invention. Also excluded from this class are the sulfoxides described above. The benefits of this invention are not obtained by merely increasing the concentration of the sulfoxide of this invention in the detergent composition.

The methyl-2-hydroxyalkyl sulfoxides of the present invention are effective at varying levels depending upon the particular organic synthetic detergent used and upon the nature of the specific sulfoxide employed. Generally speaking, the sulfoxides are effective as suds stabilizers at levels above about 0.1% in detergent compositions containing operable levels of suds-producing organic synthetic detergents.

A general type of reaction which may be employed in preparing the sulfoxides is described in detail in U.S. Patent No. 2,787,595.

The following example illustrates a method of preparing suitably pure sulfoxides for use according to the present invention.

EXAMPLE 1

A C₁₂-hydroxylated sulfoxide, specifically 2-hydroxydodecyl methyl sulfoxide, was prepared by treating dodecylene chlorohydrin, C₁₀H₂₁CHOHCH₂Cl with methyl mercaptan in sodium ethylene solution. The sulfide thus formed was oxidized with nitric acid to the hydroxylated sulfoxide, C₁₀H₂₁CHOHCH₂SOCH₃. This compound was useful as a suds stabilizing additive to a suds-producing organic synthetic detergent system; it was stable in the presence of household bleach.

EXAMPLE 2

Ingredient:	Percent
Dodecyl benzene sulfonic acid (90% active)	7.0
Sodium xylene sulfonate (37% active)	18.9
Sodium silicate (37.5% solids)	7.0
Potassium hydroxide	2.4
A C-12-hydroxylated methyl sulfoxide, C ₁₀ H ₂₁ CHOHCH ₂ SOCH ₃	3.5
Lauric isopropanol amide	1.7
Tetrapotassium pyrophosphate	19.1
Water and miscellaneous ingredients	40.4
	100.0

Example 2 represents a heavy duty liquid detergent prepared with the sulfoxide of this invention. These materials are exceptionally useful in dish washing and in heavy duty laundering. The example uses a combination of lauric isopropanol amide and a C-12-hydroxylated methyl sulfoxide as the foam stabilizing additive. The resulting detergent composition produces an exceptionally stable foam in aqueous solution and provides the required action in the presence of a bleaching agent.

EXAMPLE 3

The methyl-2-hydroxydodecyl sulfoxide prepared according to Example 1, was incorporated in a spray dried detergent composition to provide a detergent powder having the following composition:

	Percent
Na phenyltetrapropylenesulfonate	18.00
Methyl-2-hydroxydodecyl sulfoxide	3.50
Sodium toluenesulfonate	2.00
Sodium silicate solids ($\text{SiO}_2:\text{Na}_2\text{O}=2.0$)	6.00
Sodium tripolyphosphate	15.00
Tetrasodium pyrophosphate	25.00
Sodium carboxymethyl cellulose	0.50
Sodium sulfate	20.95
Misc. inert matter	2.00
	25

	Percent
Optical brighteners and antitarnish agent	0.05
Water	7.00
	100.00

5 A standard sudsing test of the composition given above and a comparison of the results obtained with those obtained with the same compositions without the sulfoxide disclosed that the sulfoxide has good suds boosting properties, and that these are evident even in the presence of hypochlorite bleach.

10 We claim:

1. Methyl- β -hydroxydodecyl sulfoxide.
